UNITED STATES PATENT OFFICE.

WILLIAM A. ZEIDLER, OF NEW YORK, N. Y., ASSIGNOR TO HURLEBURT RESEARCH CORPORATION, OF NEW YORK, N. Y., A CORPORATION OF DELAWARE.

ADJUSTING SCISSORS ELEMENT.

Application filed August 18, 1926. Serial No. 129,930.

This invention relates to a means for adjusting scissors so that the scissors blades may always be brought into proper position of alignment, either at the time of manufacture or as grinding is made necessary.

Adjusting elements generally, are not new in the art for such purposes. So far as known to applicant, there is no adjusting device which is not liable to disturbance, that is, loosening and thus giving imperfect adjustment when the scissors are in use.

The present invention is therefore directed in its object to provide a simple and efficacious means for providing an initial adjustment and maintaining it.

Referring to the drawings:

Figure 1, is an illustration of a pair of scissors with an adjustment applied.

Figure 2, is an enlarged view in fragmentary form more clearly illustrating the features.

Figure 3, is a similar view showing the two elemental parts in opposed plan view.

Figure 4, illustrates a slight modification of the engaging element.

Figure 5, illustrates the engaging elements in a further modification.

The adjusting device is applicable to shears and scissors of whatever type that is in common use. It is specifically illustrated herein, wherein the blades or cutting members of the shears or scissors are made removable and renewable.

This illustration shows the ultimate in the requirements for accurate and continued adjustments and readjustments.

In the ordinary scissors, grinding of course, from time to time, makes it necessary to effect adjustment of the scissors elements so that the blade portions will register properly and the device is perfectly adapted to take care of such adjustments as are necessary.

In the case of removable and renewable cutting blades for scissors, it is quite apparent that while the elements may be made with great perfection, the slightest micrometer difference is sufficient to require the greatest care in assembling.

In this assembling operation, there is always the fallacy of human inaccuracies, that is, the forcing of parts which necessitates adjustment before ever a perfect article is passed for market.

The present invention, therefore, serves a

double purpose. It gives any and all necessary adjustments and it provides a means of overcoming any carelessness or imperfections due to assembly. With it, the blades may be brought into absolutely perfect alignment from point to heel and in the case of renewal of blades, a new adjustment may be readily effected by the ordinary user which will be as perfect as that of the more expert artisan employed in producing goods.

The device is very simple, is somewhat unique, in its form and application.

It is illustrated as applied at the rear of the finger openings of the scissors elements A, B, which as usual, are pivoted on a usual pintle as at C, and have removable blade elements D.

At the rear of the finger openings 1, 2, are extensions 3, 4. The extension 4, as illustrated in Figures 1, 2, 3, has a transverse angular groove or opening or depression 5. This obviously may be formed transversely to the central plan of the scissors or at right angles to said plane, or in fact, at any angle.

Co-operating with this angular opening 5, is an adjusting screw 6, which, at its end 7, is chamfered, milled or otherwise formed to conform to the angular opening 5.

In any event, it is so formed that its angular sides always strike the sides of the angular opening 5, seating there against.

This device requires no locknuts or other means for preventing turning of the screw as it may be made with a fine thread and upon a 180° adjustment becomes practically a micrometer in its striking action against the opposed angular groove of the opposed element 4.

The operation of adjustment is quite obvious. When the elements and their blades are secured by a pintle, the screw 6, is turned and the scissors elements brought to the strike point until the cutting blades readjust with precision.

This is all that is necessary, inasmuch as in the opening and closing movements of the scissors elements, the engaging angular elements will always come to the strike point and hold the adjustment.

It is quite apparent that the screw will not loosen sufficiently to turn over 180° , if at all, during the opening movement of the scissors. Therefore, as the scissors are closed, each closing movement will bring it back to its properly adjusted position (in the event

of its having for any reason been moved). Thus, there is no requirement for a locked adjustment of the screw 6.

Of course, modifications might be developed along this general line which would accomplish the same general result and I have, therefore, illustrated in Figs. 4 and 5, what might be termed alternative structures or structures having a reversal of parts. For instance, in Figure 4, a pyramid shaped opening 8, is illustrated in one element, with a truncated pyramid form 9, on the end of the opposed adjusting screw. Obviously, this may be adjusted to 90° in precision.

Again, in Figure 5, the indentation in the element 4 consists of a transverse groove 10, having a central angular projection 11. Here again, the engagement is effected with a similarly formed end having a groove 12, and angularly formed sides 13, provided at the end of the adjusting screw 6.

These modifications might be carried forward in various forms, but the important requirement in any form is that the strike or articulation between the end of the adjusting screw member and the opposed surface shall be such as to cause registration and prevent a turning movement of the screw when the parts are in registration.

In other words, should the screw be slightly changed in its position with the scissors open, it will immediately come back to registration of the initial adjustment when the scissors are again closed. This feature is important as it obviates the necessity of any locking devices for the adjusting elements.

It is quite obvious that not only the modifications illustrated, but others having two opposed strike surfaces in the adjustment

devices which will maintain adjustment and alignment at each striking movement of the scissors elements, should properly fall within and be contemplated by the invention described.

What I claim as my invention and desire to secure by Letters Patent is:

1. An adjusting device for scissors comprising an angular groove in one scissors element, an adjustable screw in the opposed element, said screw having an angular face at its end for engagement with the groove of the opposed element.

2. An adjusting device for scissors comprising an angularly formed depression in the face of one element of the scissors and a cooperatively arranged angularly faced member for the opposite scissors element, one of said elements being adjustable with reference to the angle of the opposed element.

3. A combination in a pair of scissors, an extension from each element of the scissors, an angular depression in one of said elements and adjustable means in the opposite element for forming an articulating strike between the elements at any desired adjusted position thereof.

4. An adjusting device for scissors comprising one scissors element having a depression of angular form, providing a strike surface, a second scissors element having a freely adjustable strike member, with its striking end conforming to the angularly formed depression of the first named scissors element, whereby the adjustable member will be maintained in any given adjustment through its repeated engagements with the depression of angular form.

WILLIAM A. ZEIDLER.
